(57)

CLAIM

The ornamental design for the vehicle grille, as shown and described.

DESCRIPTION

FIG. 1 is a perspective view of the grille mounted lights of the present invention;

FIG. 2 is a front view thereof;

FIG. 3 is a rear view thereof;

FIG. 4 is a top view thereof;

FIG. 5 is a bottom view thereof;

FIG. 6 is a front elevation view thereof;

FIG. 7 is a rear elevation view thereof; and,

FIG. 8 is a perspective view thereof in a potential environment.

The broken lines illustrate portions of the grille mounted lights in which the design is embodied that form no part of the claimed design.

1 Claim, 6 Drawing Sheets(56)
